CLAIM

The ornamental design for a washing installation for motor cars, as shown and described.

DESCRIPTION

Fig. 1 is a perspective view of a washing installation for motor cars according to a first embodiment;

Fig. 2 is a perspective view of a washing installation for motor cars according to a second embodiment;

Fig. 3 is a perspective view of a washing installation for motor cars according to a third embodiment; and

Fig. 4 is a perspective view of a washing installation for motor cars according to a fourth embodiment.

The broken lines are for illustration purposes only and form no part of the claimed design.
